ATTORNEY

UNITED STATES PATENT OFFICE.

AUGUSTUS MISCH, OF NEW YORK, N. Y.

OIL BURNER.

Application filed November 10, 1924. Serial No. 748,907.

The present invention relates to liquid fuel burners adapted for use in heaters and furnaces, and pertains more particularly to oil burners using a low gravity oil which is inherently difficult to bring to a state of combustion, especially with a simple and inexpensive burner, such as the requirements of this trade demand.

One of the important objects of the present invention is the provision of means whereby perfect combustion of the fuel is obtained.

Another object of the invention is to provide means for giving an outward spread to the flame and inject into the same both from below and above the proper amount of air to render the fuel vapor combustible, and to attain this end without the use of blowers, compressors or like expensive and complicated mechanisms.

A further object of the invention is to provide means for obtaining a steady flame, irrespective of the changes of the draught and pressures in and around the burner.

A still further object of the invention is the provision of means whereby the fuel vapor is caused to leave the vaporizing chamber under pressure and to prevent the formation of soot at the outlet orifice of the vaporizing chamber, said means being inherent in the improved burner construction and not extraneous, as usual in devices of this type.

Still a further object of the invention is to provide a pilot burner wherein either liquid fuel or gaseous fuel may be used, and which is provided with simple and efficient means for vaporizing the liquid fuel.

Another object of the invention is to produce a burner of the type mentioned which is simple in construction, efficient in operation, durable in use and capable of manufacture on a commercial scale, or in other words one which is not so difficult to manufacture, as to be beyond the reasonable cost of such a contrivance.

With these and other objects in view, which will more fully appear as the nature of the invention is better understood, the same consists in the combination, arrangement and construction of parts hereinafter described, pointed out in the appended claims and illustrated in the accompanying drawings, it being understood that many changes may be made in the size and proportion of

the several parts and details of construction within the scope of the appended claims, without departing from the spirit or sacrificing any of the advantages of the invention.

One of the many possible embodiments of the invention is illustrated in the accompanying drawings, in which:

Figure 1 is a top plan view of a burner constructed in accordance with the present invention; and Fig. 2 is a side elevation thereof, partly in section.

In the drawings, the numeral 10 indicates a ring-shaped base, preferably in the form of a truncated cone, in which is disposed a bowl 11, the latter being supported on the base by ears 12, which project radially from the periphery of the said bowl and space the latter from said base. The ears are, preferably, disposed equidistantly, whereby a plurality of passages is formed between the bowl and base, for a purpose hereinafter to be described. The bowl is provided with a central passage 13, around which is formed an upwardly projecting flange 14. On this flange is supported a bell 15, spaced from the said flange in the same manner as the bowl 11 is spaced from the base 10. The peripheral portion 16 of the bell overhangs the flange 14. The bell is provided with a central passage 17, around which is formed an upwardly extending flange 18. On the last-mentioned flange is supported a bell 19, the latter being smaller than the bell 15, its peripheral portion 20 overhanging the flange 18 of the bell 15. The bell 19, which is spaced from the flange 18, is also provided with a central passage, denoted by the numeral 21, and around the latter is formed an upwardly extending flange 22. On this flange is supported a burner body 23, spaced from the flange 22, the said burner body having a lip 24 overhanging the flange 22. Each of the bells is provided with an annular depression 25, the purpose of which will appear hereinafter. As appears from the foregoing, air entering the base from below passes through the passages between the base 10 and the bowl 11, and between the latter and the several bells and the burner body. These passages are concentrically arranged, each of the same being wider at its entrance than at its outlet and shaped like a nozzle. The velocity of the air, as it passes through these passages, is thus increased, it passing forcibly through the

burner construction, in the same manner as if it were injected from below into the space above the burner.

The burner body 23 includes a downwardly projecting cylindrical extension 25, the same projecting centrally through the several bells, the bowl 11 and the base 10, and extending also through a bar 26 which is placed against the bottom of the base 10, all of the elements being united by a nut 27, which bears against the underface of said bar. The cylindrical extension is provided with a bore 28, to which leads a fuel supply pipe 29. Any suitable means may be provided for regulating the flow or feed of fuel through the pipe 29, fuel being fed to the bore 28, which is part of the fuel conduit, by gravity. In the bore 28 is disposed a nozzle 30, having a restricted outlet opening 31. Below this nozzle the bore 28 is restricted, as shown at 32, the communication between the restricted portion 32 of the bore and the nozzle being controlled by a check valve 33. The outlet of the nozzle 30 is disposed a substantial distance below the outlet of the bore 28, and above the latter outlet is supported a conical spreader piece 34, to spread the vapor as it leaves the burner body 23. That portion of the bore 28, which is disposed between the lower end of the nozzle and the check valve, constitutes a vaporizing chamber, denoted by the numeral 35. As appears from Fig. 2 of the drawings, the spreader piece restricts the outlet of the bore 28. The velocity of the fuel vapor will thus be increased, as it leaves the fuel conduit.

The bowl 11 is provided at diametrically opposite portions thereof with two openings 36, which are connected by a yoke-shaped pipe 37, the latter extending across the said bowl above the burner body 23. In alignment with the said burner body, the pipe 37 is provided with a downwardly directed outlet 38, in the form of a nozzle. By this nozzle air, entering the openings 36, is directed against the burner body 23. The areas of the openings 36 are considerably in excess of the area of the outlet 38, so that a downward draft of air is directed against the vapor and the flame leaving and disposed, respectively, above the burner body 23.

In the bowl is provided an overflow opening 39, connected with an overflow pipe (not shown), as usual in constructions of this type. On the underface of the bowl 11 is furthermore provided a vaporizing chamber 40, to which leads a fuel supply pipe 41. This vaporizing chamber is connected by an aperture 42 with a pilot burner 43, the lower end of which communicates through small perforations 44 with the atmosphere. If the pilot burner is to be used in connection with liquid fuel, the latter is led into the vapor-

izing chamber 40, which is pre-heated by a torch or other means, whereby the liquid fuel is vaporized, the liquid passing through the aperture 42 into the pilot burner chamber 43, drawing air through the perforations 44, so that the vapor burns within the burner chamber in the same manner as in a Bunsen burner. It is obvious that where coal gas or other gas is available, the pilot burner herein described may be used in connection therewith.

The operation of this device is as follows: After initial heat has been applied to the burner until the same is thoroughly heated and the pilot burner has been lit, the valve 80 controlling the fuel supply pipe 29 is slowly opened. The liquid fuel raises the check valve 33 and passes into the vaporizing chamber 35, wherein it is immediately vaporized. The vaporized fuel passes then through the nozzle 30 and leaves the burner body 23 forcibly by reason of a vacuum which is produced above the burner in a manner hereinafter to be described, and is then ignited by the pilot light. The flame 90 so produced causes a vacuum above the burner, drawing air through the concentric air passages between the base 10, bowl 11, the several bells and the burner body 23, the natural draft in the chimney connected 95 with the burner producing air pressure for the same purpose, so that air sufficient for complete combustion of the oil and vapor is continuously obtained. The spreader 34 spreads the vapor outwards toward the wall 100 of the furnace or the like. At the same time a jet of air is directed downwardly against the flame, the said jet not only aiding in the spreading of the flame but furnishing air to the upper surface of the 105 flame. The concentric air passages are disposed one above the other, so that the air is evenly distributed all over the flame, a fact which aids considerably in the complete combustion of the fuel. By actual 110 experiments it has been shown that the combustion is so perfect that no smoke or noxious fumes are emitted from the burner. The check valve 33 is provided to prevent the oil vapor in the vaporizing chamber 35 115 from exerting pressure on the liquid fuel. If this check valve were not provided, the flame would be unsteady.

Any oil which may escape without being converted into vapor flows down the lip 24 120 on the burner body 23 into the depression 25 in the bell 19, and when this depression is filled into the depression in the bell 15. When this latter depression is filled, the oil flows into the bowl 11, and thence through 125 the overflow opening 39 into the pipe connected with the latter. This will occur, of course, only in case the flame has been extinguished. In efficient operation of this burner, the oil is consumed as it issues from 130

the fuel conduit. However, if for some reason it should not be converted fully into vapor in the vaporizing chamber, the liquid fuel, as it flows toward the bowl 11 in the 5 manner referred to, is converted into vapor by the highly heated bells.

Attention is called to the fact that, while herein two bells have been shown and described, any other suitable number may be 10 employed without departing from the invention. It will be noted from the foregoing that in the burner herein described perfect combustion is obtained; the flame is always steady; and that soot cannot form 15 in the fuel conduit 28 by reason of the fact that the vapor is forcibly ejected therefrom, as hereinabove described. It is also to be noted that an oil burner constructed in accordance with the present invention is ex- 20 tremely cheap and simple, is very durable, and is adapted to be used successfully in furnaces, stoves, etc.

What I claim is:

1. A liquid fuel burner including a ring- 25 shaped base, a plurality of superposed ring-

shaped bodies on said base, the lowermost of said bodies being spaced from said base and others being spaced from one another and from said lowermost body, whereby a plurality of concentric passages is formed, 30 each of said passages having an inlet larger than its outlet, a fuel conduit extending centrally through said base and said ring-shaped bodies, the lowermost of said ring-shaped bodies being provided with two 35 openings at diametrically opposite portions thereof, and a yoke-shaped tube connecting said openings, said tube being disposed above said base and said ring-shaped bodies and having an outlet directed downwardly 40 upon said ring-shaped bodies.

2. In a liquid fuel burner according to claim 1, the area of the outlet of said yoke-shaped tube being considerably smaller than the combined areas of said openings. 45

Signed at New York, in the county of New York, and State of New York, this 6th day of November, A. D. 1924.

AUGUSTUS MISCH.
